UNITED STATES PATENT OFFICE.

GEORGE H. GILMAN, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

PRESSURE-ACTUATED VALVE.

1,164,497.

Specification of Letters Patent. Patented Dec. 14, 1915.

Application filed February 10, 1913. Serial No. 747,295.

To all whom it may concern:

Be it known that I, GEORGE H. GILMAN, a citizen of the United States, and a resident of Claremont, county of Sullivan, State of New Hampshire, (whose post-office address is Claremont, New Hampshire,) have invented an Improvement in Pressure-Actuated Valves, of which the following description, in connection with the accompanying drawings, is a specification, like characters on the drawings representing like parts.

This invention relates to pressure-actuated valves and more particularly to valves intended for direct-acting engines, such as are employed in connection with rock drilling machines.

The invention will be best understood by reference to the following description when taken in connection with the accompanying illustration of one specific embodiment thereof, while its scope will be more particularly pointed out in the appended claims.

In the drawings: Figure 1 is a longitudinal section of my improved valve as applied to a drill; Fig. 2 is a plan view of a portion of the cylinder showing the relation of the ports; and Fig. 3 is a section on the line 3—3 of Fig. 1.

Referring to the drawings and to the embodiment of my invention therein shown, I have illustrated the same as applied to a rock drilling engine having the cylinder 1, the piston 2, the latter having a contracted portion 3 between its ends which forms an annular chamber around the piston. This chamber may be provided with a vent 4. The piston rod 5 secured to the piston projects through the front head 6 and is attached to the drill bit, not herein shown.

The cylinder is provided with inlet ports 7 and 8, the former leading to the forward end of the cylinder and the latter to the rearward end thereof. It is also provided with valve-reversing ports 9 and 10 which lead to opposite ends of the valve chamber, as will be more fully explained.

The valve chest 11 is provided with ports 12 and 13 which communicate respectively with the cylinder inlet ports 7 and 8. It is also provided with a centrally arranged admission port 14 which communicates with the port 15 and the admission passage 16. It is also provided with the exhaust ports 17 and 18 which communicate with the port

19 and the exhaust passage 20. The valve 55 chest is provided with the valve chamber 21 which receives the piston valve 22, the latter having the opposite piston heads 24 and 25 of substantially the same diameter and the intermediate but larger piston head 26. 60 The opposite ends of the valve chamber are closed by the buffers 27 and 28, respectively.

It will be observed that the inlet port 7, which leads to the forward end of the cylinder, communicates with the valve chamber 65 at the rear of the piston head 26, while the inlet port 8, which leads to the rearward end of the cylinder, communicates with the valve at the forward side of the piston head 26. This brings the inlet ports 7 and 8 into 70 crossed relation. It will also be observed that the reversing ports 9 and 10 do not have this crossed relation, but lead directly to the cylinder port 9, which opens at the rearward end of the valve chamber communicating 75 with the rearward end of the main cylinder and the port 10 which communicates with the forward end of the valve chamber leading to the forward end of the cylinder.

The operation of the valve is as follows: 80 In the position shown, pressure fluid is being admitted from the admission passage 16 through the port 15 to the admission port 14. From here it passes through the valve chamber to the admission port 8, 85 passing into the rear of the cylinder and acting to drive the piston forward. During this movement of the piston the valve is held in the assigned position by the pressure of the admission fluid acting against the 90 larger piston 26 of the valve, the rear end of the valve chamber being vented through the port 9 and the vent opening 4. Meanwhile pressure fluid is exhausted from the forward end of the cylinder through the 95 port 7, valve chamber port 12, ports 17—19 and passage 20. This condition holds until the rear edge of the piston has passed the port 9, whereupon pressure fluid is admitted to the rear end of the valve chamber and 100 acts against the piston head 24 of the valve to throw the same into a reverse position. In this position of the valve pressure fluid is admitted to the forward end of the cylinder through the ports 12 and 17 and is exhausted from the rearward end of the cylinder through the ports 8, 13 and 18. The 105 valve chamber is provided with the lining

sleeve 29 which is cut away to provide access to the ports 13 and 18. In the reverse position of the valve, also the latter is held by admission pressure acting against the 5 rear face of the larger piston head 26, and the forward end of the valve chamber soon becomes vented through the port 10 after the same has been opened to the annular space surrounding the contracted portion of 10 the piston 3. Thus the pressure of the actuating fluid which enters through the port 14 holds the valve against the one or the other of the two buffers until the piston has passed the reverse port so that unless the 15 reverse port has been opened the valve port cannot be accidentally thrown or displaced.

Heretofore it has been customary to reverse the valve by means of reverse ports which connect the forward and rearward 20 ends of the valve chamber with the rearward and forward ends of the cylinder respectively. By so arranging the inlet and reverse ports so that the ports may lead directly to the cylinder and connect the rearward and forward portions of the valve chamber with the rearward and forward portions of the cylinder, respectively, a quicker action is secured for the reversing 25 valve.

30 While I have herein shown and described for purposes of illustration one specific form of the invention, it is to be understood that the same is not limited to the details of ports or the relative arrangement of the 35 same, but that extensive deviations may be made therefrom without departing from the spirit of the invention.

Claims:

1. In a valve mechanism the combination 40 with a cylinder having inlet and exhaust ports, a piston, a piston valve controlling said ports, said valve having pistons at each end thereof and a member intermediate thereof carrying opposed pressure areas, 45 said intermediate member presenting greater areas than either of said end ones, and said

cylinder having reversing ports in the forward and rearward portions thereof leading to the forward and rearward ends respectively of said piston valve, means for 50 admitting pressure in alternation to said reversing ports at each stroke of the piston, the opposite port in each case being vented to lower the pressure therein whereby said piston valve is unbalanced when the piston 55 passes the reversing ports.

2. In a valve mechanism, the combination with a cylinder having inlet and exhaust ports, a piston having front and rear heads with an intermediate contracted portion to provide a space within the cylinder between said contracted portion and the piston heads, a pressure actuated valve controlling said ports, said valve having pistons at each end thereof and a member intermediate thereof carrying opposed pressure areas, said intermediate members presenting greater areas than either of the end ones, said cylinder having inlet ports for the forward and rearward end thereof communicating with the valve chamber respectively at the rearward and forward ends of said member of greater area and having also reversing ports in the upper and lower portions thereof leading to the lower and 70 upper ends respectively of said piston valve, each reversing port in the cylinder being adapted to be uncovered by the corresponding piston head first on one side thereof and then on the opposite side and means for 75 venting the chamber surrounding the intermediate portion of the piston whereby said piston valve is unbalanced when the piston passes the reversing ports.

In testimony whereof, I have signed my 80 name to this specification, in the presence of two subscribing witnesses.

GEORGE H. GILMAN.
